UNITED STATES PATENT OFFICE.

VERNER E. ERWIN, OF LIMA, OHIO.

GAME.

Specification of Letters Patent.

Patented Feb. 7, 1922.

1,405,988.

Application filed February 25, 1921. Serial No. 447,652.

To all whom it may concern:

Be it known that I, VERNER E. ERWIN, a citizen of the United States, residing at Lima, in the county of Allen and State of Ohio, have invented new and useful Improvements in Games, of which the following is a specification.

This invention relates to games and comprehends a structure embodying a checkered board and a predetermined number of game pieces, divided into sets to represent and symbolize persons and things and the duty performed by such in actual war.

The nature and advantages of the invention will be better understood when the following detail description is read in connection with the accompanying drawings, the invention requiring the exercise of considerable skill, which fact assures both interest and amusement to the players.

In the drawings forming part of this application like numerals of reference indicate similar parts in the several views and wherein:

25 Figure 1 is a plan view of the checkered board or playing surface on which the game is played.

30 Figure 2 is a view of one of the game pieces which represents the "Capital" and of which there are two.

Figure 3 represents the "President" of which there are two.

Figure 4 represents the "General" of which there are four.

35 Figure 5 represents the "Cavalry" of which there are four.

Figure 6 represents an "Airplane" of which there are four.

Figure 7 represents the "Navy" of which 40 there are four.

Figure 8 represents a "Tank" of which there are four.

Figure 9 represents "Transportation" of which there are four.

45 Figure 10 represents "Home" of which there are four.

Figure 11 represents the "Infantry," of which there are thirty-two.

Figure 12 is a plan view of the playing board showing the initial arrangement of the game pieces thereon.

The game apparatus forming the subject matter of my invention embodies a playing board or surface 10 which is marked off 50 similar to the well known checker board, the latter being provided with at least sixteen

rows of squares, each row having at least sixteen squares. There are two sets of game pieces, one set for each player, and each set comprising thirty-two pieces. The respective game pieces of each set are of different designs to represent and symbolize to a marked degree persons and things utilized in actual warfare. Each set of game pieces includes one "Capital", one "President", two "Generals", two "Cavalry", two "Transportation", two "Tanks", two "Navy", two "Home", two "Airplanes", and sixteen "Infantrymen". The game pieces of the respective players, except the "Infantry", are arranged initially upon the playing board as shown in Figure 3, wherein the game pieces extend across the entire width of the playing board occupying the outermost row of squares. The sixteen "Infantrymen" of the respective players are extended across the entire width of the board occupying the next row of spaces as illustrated in Figure 3.

The principle of this game is based on "Republic", "Government" and the "World War" which has just ended. It is the object of each player to protect his "Capital" at all times and at any cost and to capture the opponent's "Capital." This may be done by forcing the opponent to position his "Capital" so that it cannot be moved without capture. The game pieces are moved alternately by the respective players across the board either way and any distance, but must occupy the same color of squares that they occupied initially. As the "Infantrymen" occupy the entire second row of spaces on the playing board, these game pieces must be moved first, and they may initially be moved at least three spaces at one time, but thereafter only one or two spaces. The "Infantrymen" must be moved straight ahead except when taking a man of the opponent player, should the latter occupy a position diagonally to the position occupied by the "Infantrymen" of one player, taking one of the game pieces of the opponent. Occupying position of game piece taken. The "Capital" of each player should be protected by the other game pieces, and each player should exercise skill in having the "Capital" surrounded by different persons and organizations represented and symbolized by the other game pieces. The game pieces, except those representing the "Infantrymen", can never be jumped and taken in that manner except

with "Airplanes" and "Tanks," and in these instances the game pieces cannot be taken unless the game piece executing the jump occupies the space formerly occupied by the game piece taken.

5 The "President" can move in any direction and any distance but must move on a straight line from the starting point, while the "Generals" may move any distance across 10 the board providing that at the termination of the move in a straight line they are subsequently moved one space to the right or left.

15 The "Airplanes" may move two spaces and then may be moved two spaces in any direction, but each two spaces must be on straight lines, it being understood that the "Airplanes," while occupying a "Fort" indicated by F in Figure 1, cannot be captured by any 20 of the opponent's game pieces except those indicating "Tanks," and Airplane.

25 The game pieces representing the "Navy" may be moved two spaces at a time, no more or no less, but in any direction.

30 The game pieces representing the tanks must be always moved three spaces, two one way and one the other, and as above stated, the "Tanks" and Airplane are the only game pieces that can capture an "Airplane" while occupying a "Fort."

35 The "Cavalry" always moves diagonally any distance across the board and subsequent to this move must move one space either to the right, left, or an opposite direction to its initial movement.

40 The game pieces representing "Home" may be moved any distance at one time, always across the board.

45 The character of the game is such as to require the exercise of good judgment and discretion to successfully play the game, and is particularly useful in developing the mind of the players. The playing board may vary in size to include any number of spaces or squares, and the number of game pieces

in each set may also vary, and the component elements constructed from any suitable material and in any design without departing from the spirit of the invention.

45 While it is believed that from the foregoing description the nature and advantages 50 of the invention will be readily apparent, I desire to have it understood that I do not limit myself to what is herein shown and described, and that such changes may be resorted to when desired as fall within the 55 scope of what is claimed.

What is claimed is:

1. A game apparatus comprising a checkered board having a plurality of parallel rows of squares of sixteen squares each, the 60 board being further marked to define a large central square, the corners of which represent "Forts," two sets of game pieces representing and symbolizing persons and things utilized in actual war, each set including 65 sixteen pieces of different representations arranged on a straight line across one side of the board with each piece occupying a space, and the remaining sixteen pieces having a given representation and initially arranged 70 to occupy the next parallel row.

2. A game apparatus comprising a checkered board having parallel rows of sixteen squares each, the alternate squares of each 75 row being of different colors, certain squares of one row being characterized as stations of organizations, game pieces representating such organizations occupying said stations, other game pieces representative of persons and things used in warfare occupying the 80 other spaces of said row, a plurality of game pieces of the same representation initially occupying the next parallel row of spaces, and said board being centrally marked off to provide a square, the corners of which represent "Forts."

In testimony whereof I affix my signature.

VERNER E. ERWIN.
